G. W. COEN

OIL HEATER

Filed Sept. 28, 1921

Fab. 1.

Fig. 2.

INVENTOR
GARNET W. COEN

BY Chas. E. Duncand
ATTY.

UNITED STATES PATENT OFFICE.

GARNET W. COEN, OF SAN FRANCISCO, CALIFORNIA.

OIL HEATER.

Application filed September 28, 1921. Serial No. 503,728.

To all whom it may concern:

Be it known that I, GARNET W. COEN, a citizen of the United States, residing at the city and county of San Francisco and 5 State of California, have invented new and useful Improvements in Oil Heaters, of which the following is a specification.

This invention relates to liquid heaters and especially to a simplified form of the 10 structure shown in my co-pending application entitled, "Oil heater" filed April 13, 1921, Serial No. 461,078.

One of the objects of the present invention is to generally improve and simplify 15 the construction of oil heaters and especially to provide a structure which will permit a maximum heat transfer to be obtained between the heating medium and the oil or liquid to be heated; high efficiency being obtained in this instance, first, by maintaining 20 the oil in ribbon or film-like condition during its passage through the heater, second, by maintaining the oil in a state of agitation by a high velocity; and third, by providing an exceedingly large heating surface 25 which the steam or other heating medium employed can efficiently act upon.

Another object of the invention is to construct a heater which may be readily taken 30 apart for inspection, repairs, etc., but particularly for the purpose of cleaning the same, and which when taken apart will present an exposed surface readily accessible for cleaning by scraping, brushing, or otherwise.

Another object of the invention is to provide a heater which is simple, compact, and substantial in construction, cheap to manufacture and in which all parts are free to 40 expand without danger of imposing strains on the assembled or connected parts. Further to provide a structure in which stuffing boxes and like connections may be eliminated, thus avoiding leakage both of the liquid to be 45 heated and the heating medium employed.

Other objects will hereinafter appear.

The invention consists of the parts and the construction and combination of parts as hereinafter more fully described and 50 claimed, having reference to the accompanying drawings, in which—

Figure 1 is a central, vertical, longitudinal section through the heater.

Fig. 2 is a cross section taken on line 2—2, 55 Fig. 1.

Crude oils or residuum such as employed

today for fuel purposes, and particularly crude oils derived from an asphalt base are becoming thicker and more viscous as time passes due to the greater extraction of gasoline, kerosene and other by-products. Crude oils of this character when obtained from the refiners are often so thick and viscous that the oil must be heated to a temperature of from 200 to 300 degrees Fahrenheit before it is rendered sufficiently liquid to be readily handled and efficiently atomized by the burners. The heating of fuel oil is therefore not only a necessity, due to the reasons specified, but it also presents a difficult problem in actual practice as the heaters rapidly lose their efficiency due to the formation of deposits of carbon, asphalt, sand, etc., on the surfaces through which the heat transfer takes place. Such deposits are, practically speaking, non-conductors of heat and they form a coating which bakes and hardens on the heat transferring surfaces and furthermore gradually clogs the passages through which the oil is forced. It can therefore be readily seen that unless such accumulations or deposits are removed from time to time, the heater will become so inefficient as to be practically useless.

Having these problems and conditions to encounter, I have developed a heater which is particularly adapted to handle crude oils such as referred to and which will efficiently heat a given volume of oil if cleaned from time to time. One of the main features of the present invention is, therefore, the provision of a heater which permits a maximum heat transfer at all times and which may be readily and quickly taken apart for cleaning whenever necessary; further a heater in which the steam or heating medium employed may be utilized to obtain the greatest efficiency possible. I have accordingly constructed a heater consisting of two inter-spaced cylindrical shells or casings adapted to telescope or nest one within the other, as indicated at 2 and 3. These casings are inter-spaced as shown to form a liquid flow passage 4 and a centrally disposed heating chamber 5. The outer shell or casing 2 is closed at its upper end by means of a head member 6 which in this instance forms an integral part of the casing. The lower end of the casing is open to receive the inner casing 3, but is provided with an annular outwardly extending flange 7, the function of which will hereinafter be described. The

inner shell or casing 3 is similarly provided with an integral head member 12 and the lower end of the casing is also provided with an outwardly extending annular flange 14. The lower end of the casing is closed by means of a bottom head member 15 which is welded or otherwise secured as shown at 16.

Surrounding the inner shell 3 is a spiral shaped spacing member 19. This member is welded or otherwise secured to the exterior face of the inner casing and serves two functions: first, that of maintaining a predetermined spacing between the shells 2 and 3, and second, that of forming a spiral shaped passage through which the oil or liquid to be heated must pass during its flow through the heater. The inlet for the oil is formed at the point indicated at 20 and this inlet is connected through the medium of a pipe 21 with a pump not shown, which will force the oil through the heater at a comparatively high velocity. The oil, in other words, enters the lower end of the spiral shaped passage, discharges from the upper end of said passage into a chamber 22 formed between the head members 6 and 12 and it is finally discharged through a pipe 23, preferably welded to the upper head 6 as indicated at 24. The lower head member 15 is provided with two openings through which passes a steam inlet pipe 25 and an outlet pipe 24^a. Both pipes are welded with relation to the bottom section 15 to avoid the use of stuffing boxes or similar connections. The inlet pipe is connected with a boiler or other suitable source of supply, while the discharge pipe 24^a, through which the condensate discharges, is connected with a trap or other means not here shown.

As previously stated in the specification one of the features of the present invention is to permit removal or separation of one shell or casing with relation to the other. To permit such removal it is obvious that a sliding or telescoping fit must be maintained between the two casings. Further, that means must be provided which permits the casings to be readily secured with relation to each other or released when separation or removal is required. This is accomplished by flanging the lower ends of the respective casings as indicated at 7 and 14. A gasket 30 is placed between the flanges and the flanges are drawn together by means of a pair of clamping rings 31 and 32 and by bolts passing therethrough as indicated at 33. By placing the bolts as shown in Figs. 1 and 2, it is obvious that drilling of the flanges 7 and 14 is avoided, thus materially reducing the cost of manufacture.

If it is desired to remove the inner casing or shell 3, it is accomplished by releasing the bolts 33 and removing the lower clamping ring 32. When this has been accomplished,

it will only be necessary to exert a pull either on the outer or on the inner casing. The two casings will then separate and the respective surfaces exposed to the oil will then be in readiness for cleaning, by scraping, brushing or otherwise. After the cleaning operation has been accomplished, it is only necessary to assemble the casings and to replace the clamping rings 31 and 32 and the bolts 33; a gasket 30 being of course interposed between the flanges 7 and 14 to maintain an oil tight joint. It can therefore be seen that the operation of separating and cleaning the respective parts of the heater is very simple and may be readily and quickly accomplished whenever desired; further that leakage of the oil is reduced to a minimum due to the fact that a single packing surface, or that indicated at 30, is all that is required. Again, that stuffing boxes and the like may be entirely eliminated and leakage of either oil or the heating medium prevented as the pipes 21, 24^a and 25 are all welded with relation to the head member 15 and the casing 3.

While certain features of the present invention are more or less specifically illustrated, I wish it understood that various changes in form and proportion may be resorted to within the scope of the appended claims, similarly that the materials and finish of the several parts employed may be such as the experience and judgment of the manufacturer may dictate or varying uses may demand.

Having thus described my invention, what I claim and desire to secure by Letters Patent is—

1. A heater comprising a pair of concentric cylindrical telescoping shells, said shells being interspaced to form an annular liquid flow passage between the shells, an integral head member for each shell forming a closure for the upper end thereof, said heads being interspaced, a head member forming a closure for the lower end of the inner shell and welded thereto, said head member forming an inner heating medium chamber, means for circulating a heating medium therethrough, means for admitting oil to the lower end of the annular flow passage, means for discharging the oil from the upper end thereof, an annular outwardly extending flange formed on the lower end of each shell and one disposed on top of the other, and an annular clamping member engaging the flanges.

2. A heater comprising a pair of concentric cylindrical telescoping shells, said shells being interspaced to form an annular liquid flow passage between the shells, an integral head member for each shell forming a closure for the upper end thereof, said heads being interspaced, a head member forming a closure for the lower end of the inner shell

and welded thereto, said head member forming an inner heating medium chamber, means for circulating a heating medium therethrough, means for admitting oil to the lower 5 end of the annular flow passage, means for discharging the oil from the upper end thereof, an annular outwardly extending flange formed on the lower end of each shell and one disposed on top of the other, a gasket 10 interposed between the flanges, an upper and a lower annular clamping ring engaging the respective flanges, and bolts connecting the respective clamping rings.

3. In a heater of the character described, 15 the combination with an inner and an outer shell, of an annular outwardly extending flange formed on the lower end of each shell, said flanges being disposed one on top of the other, a gasket adapted to be interposed between 20 said flanges, a pair of rings disposed one above and one below the flanges, and bolts extending through the rings to draw the rings and the flanges together.

4. In a heater of the character described 25 an inner and an outer cylindrical shell, said shells being interspaced with relation to each other to form an annular liquid flow passage, an annular outwardly extending flange formed on the lower end of each shell, 30 said flanges being disposed one above the other, a packing member interposed between the flanges, means for drawing the flanges together, a head member secured in the lower end of the inner shell, an inlet and an outlet pipe connected with said head member, 35 and a delivery pipe connected with the lower end of the inner shell and communicating with the annular flow passage.

5. In a heater of the character described 40 an inner and an outer cylindrical shell, said shells being interspaced with relation to each other to form an annular liquid flow passage, an annular outwardly extending flange

formed on the lower end of each shell, said flanges being disposed one above the other, 45 a packing member interposed between the flanges, means for drawing the flanges together, a head member secured in the lower end of the inner shell, an inlet and an outlet pipe connected with said head member, 50 a delivery pipe connected with the lower end of the inner shell and communicating with the annular flow passage, a spiral shaped spacing member secured on the exterior surface of the inner shell and extending from 55 end to end thereof, a pair of interspaced head members one for each shell forming a closure for the upper end thereof, and an outlet pipe connected with the head member 60 on the exterior shell.

6. In a heater of the character described an inner and an outer cylindrical shell, said shells being interspaced with relation to each other to form an annular liquid flow passage, an annular outwardly extending flange 65 formed on the lower end of each shell, said flanges being disposed one above the other, a packing member interposed between the flanges, means for drawing the flanges together, a head member secured in the lower 70 end of the inner shell, an inlet and an outlet pipe connected with said head member, a delivery pipe connected with the lower end of the inner shell and communicating with the annular flow passage, a spiral shaped 75 spacing member secured on the exterior surface of the inner shell and extending from end to end thereof, a pair of interspaced head members one for each shell forming a closure for the upper end thereof, and an outlet pipe connected with the head member 80 on the exterior shell, the head member on the upper end of the inner shell being concaved to form a deflecting surface.

GARNET W. COEN.
